UNITED STATES PATENT OFFICE.

TADEUSZ ZDRODOWSKI, OF PITTSTON, PENNSYLVANIA.

TOILET ARTICLE.

1,113,727.

Specification of Letters Patent. Patented Oct. 13, 1914.

Application filed April 24, 1914. Serial No. 834,285.

To all whom it may concern:

Be it known that I, TADEUSZ ZDRODOWSKI, a subject of the Czar of Russia, residing at Pittston, in the county of Luzerne and State 5 of Pennsylvania, have invented certain new and useful Improvements in Toilet Articles, of which the following is a specification.

This invention relates to toilet articles.

The primary object of this invention is 10 to provide a hair brush and comb in a unitary structure and adaptable for use either singly or collectively.

A still further object is to provide a hair brush with a comb operatively positioned 15 substantially centrally thereof and designed for removal for individual use if desired.

A still further object is to provide a hair brush with a slidably-mounted comb positioned among the bristles thereof and re- 20 movable when desired upon releasing a retaining latch therefor.

With these general objects in view and others that will appear as the nature of the invention is better understood, the same con- 25 sists in the novel combination and arrangement of parts hereinafter fully described, illustrated in the accompanying drawings, and pointed out in the appended claims.

In the drawings forming a part of this 30 application and wherein like designating numerals refer to corresponding parts throughout the several views:—Figure 1 is a longitudinal central sectional view through the bristle portion of the present form of hair brush. Fig. 2 is a bottom plan view of the device assembled for collective use. Fig. 3 is a transverse sectional view taken upon line III—III of Fig. 1, and, Fig. 4 is 35 a front elevation of the device showing the retaining slide elevated in dotted lines.

Referring more in detail to the drawings, the hair brush 10 is illustrated provided with the usual handle 11 and the bristles 12 positioned upon the face 13 of the oval-shaped back 14. The face 13 of the brush back is provided with a central longitudinal groove 15 substantially circular in cross-section and adapted to receive the cylindrical back or base 16 of a comb having a body 17 45 and the usual form of teeth 18. The comb being slidably-mounted within the groove 15, it will be seen that the comb is readily inserted or removed from its position with-

in the body of projecting bristles 12. A latch or slide 19 is positioned slidably and 55 in a slot 20 at the outer end of the brush back 14 and adapted when in seated position to traverse the groove 15, thus preventing the removal of the slidable comb but when positioned outwardly as shown in 60 dotted lines in Fig. 4, allowing the comb to be removed by uncovering the end of the groove. The latch 19 is provided with a base flange 21 adapted to engage the cross-piece 22 at the top of the slot 20 for pre- 65 venting the entire removal of the latch from its receiving slot.

The complete operation of the device will be apparent from the detailed description thereof in that the comb 17 when positioned 70 within the bristles of the brush, is adapted to be employed therewith for a simultaneous brushing and combing operation upon the hair while if desired to employ the brush or the comb separately, the latch 19 is withdrawn and the comb slidably removed from the brush, and after being used is readily replaced in its assembled position. 75

While the forms of the invention herein shown and described are what are believed 80 to be preferable embodiments thereof, it is nevertheless to be understood that various forms and modifications may be resorted to which fall within the spirit and scope of the invention as claimed. 85

What I claim as new is:—

1. A device of the class described comprising a brush back provided with bristles upon one face thereof and with a longitudinal groove in the said face closed at its inner end and open at its outer end positioned between the said bristles, a comb slidably-mounted in the open outer end of said groove, a vertically movable latch slidably-mounted upon the brush positionable trans- 90 versely of said groove, and stop means for said latch. 95

2. A device of the class described comprising a brush back having bristles upon one face thereof and further provided with a longitudinal groove substantially circular in cross-section closed at its inner end and open at its outer end intermediately-positioned within said bristles, a comb having a substantially cylindrical back and slidably-mounted in the open outer end of said 100 105

groove, the free end of said back being provided with a transverse slot, a latch slidably-positioned within said slot and traversing said groove, a spanning member across said slot, and a stop flange upon said latch positioned in alignment with said spanning member.

In testimony whereof I affix my signature in presence of two witnesses.

TADEUSZ ZDRODOWSKI.
